UNITED STATES PATENT OFFICE.

GUSTAV FRIEDRICH GIEHLER, OF CHEMNITZ, GERMANY.

DRIVER OR PICKER APPARATUS FOR LOOMS.

Application filed June 6, 1925, Serial No. 35,393, and in Germany August 26, 1924.

As is known, the driver or picker devices in looms irrespectively of whether they are driven by over-beaters, under-beaters, spring power or the like, present a number of disadvantages, such as considerable consumption of power, vibration of the loom, heavy construction, excessive wear, and disturbances of working resulting from wear of the parts and stretching of the belts. In order to remove these disadvantages a start has been made by omitting the picker altogether and exerting a driving action directly on the shuttle. For this purpose continuously rotating discs are utilized which from time to time are brought into contact with the shuttle. The latter must then however be of a special form, such that the discs can come into contact with projecting ledges on the shuttle body. The devices in question are complicated and have not been adopted to any extent in practice.

The present invention also makes use of continuously rotating friction discs, but does not let them act directly on the implement (shuttle), but the discs which are utilized singly or in numbers, act upon a slide carrying a driver or picker device so that the driver device in its turn drives the shuttle which may be constructed in the usual way.

Slide-block driving is known in itself. In the known method however the slide acts directly or is itself directly subjected to the beating device. The vibrations are not eliminated. It is a question primarily only of a driving device such as those mentioned at the beginning with the defects there set forth. According to the invention, however, the slide is only an intermediate member for uniting the advantages of the friction-disc drive with the movement by drivers or pickers which is advantageous for the implement, that is to say, for the purpose of still exerting a powerful blow on the implement without causing vibration of the loom mechanism.

The device is very simple and guarantees a sure result. It may be employed not only for driving the shuttles but also for driving all the other implements to which a reciprocating movement has to be imparted in weaving, such as skewers and the like, wherein in all these implements can retain their customary form.

The slide is accelerated gradually and therefore without shock from the position of rest by the friction discs rotating at a high speed and then takes up very quickly the velocity requisite for shooting the shuttle through. The slide then runs between the shoes of a brake which intercepts it without shock. When the requisite velocity of the slide is reached, the discs may be moved away from it or rendered inoperative by the keyway of the slide in which the pulley engages being widened at a particular point in such a way that the frictional closure is thereby eliminated.

If the forward travel of the slide has to take place at a comparatively high velocity, substantially more time is available for its return movement, so that this can be executed comparatively slowly. According to the invention, for the return movement, another friction disc, likewise continuously running, is utilized, which is rotated in the opposite direction to the forward driving disc and more slowly, and comes into engagement, owing to a reversing control, after the forward driving disc has been moved away from the slide, so that the latter cannot even by accident come into contact with the retracted slide.

In the accompanying drawings one constructional example of the invention is illustrated.

Figure 1 shows a partial side elevation, Figure 2 a partial cross section on the line $\alpha-\alpha$ in Figure 1 on a larger scale;

Figure 3 an end view, and Figures 4 and 5 altered positions of the essential parts.

According to Figure 1, the shuttle, not shown, rests in a support consisting of two guiding rails 1, 1, secured to the lathe or sley 2 vertically one above the other. It has to be thrown by the driver 3, which is supported under the action of the spring 4 in the holder 5, in a manner known in itself. The holder 5 is mounted on the slide 6, which rests in a box-shaped guide 7 secured to the lathe beam 8.

On the lathe beam 8 is also supported a bell-crank lever 9 oscillatable about the pivot 10, one arm of said lever carrying two friction discs 11. They may engage with their wedge-shaped rims in correspondingly wedge-shaped grooves or keyways 12 in the slide 6 (Figure 2). The bell-crank lever 9 furthermore carries two smaller discs 13, with wedge-shaped edges, which can engage in the keyways 12 of the slide. The discs 11 and 13, projecting through slots in

the guide 7, are connected with one another by a crossed belt 14. On the common shaft of the two discs 11 there acts a quarter-twist belt 15 the driving pulley of which can be set in rapid rotation by an electric motor or other drive. To an extension 9' of the bell-crank lever 9 there is attached a controlling means in the form of a rod, a cord of wire 17. If the controlling means 17 is to act only by a downward pull, provision must be made by means of a counter-balancing weight or spring for the rocking movement of the bell-crank lever 9 in the other direction.

15 In Figure 5 is to be found the brake not shown in Figure 1, located, in the direction of the drawing at an appropriate distance to the left of the pulley 11. This brake consists of a stationary block 18 and a movable block 19. On the block 19 there acts a controlling means 20 consisting of a cord or the like, while the block 19 is normally held in the braking position by means of a spring or the like.

20 25 In the case of the right-hand shuttle drive illustrated, the two-fold disc 11 illustrated enters, owing to the movement of the arm 9' or of the controlling means 17 in the direction indicated by the arrow, into the slide grooves 12, and in consequence of its rapid rotation accelerates the slide towards the left, the driver 3 shooting the shuttle out of its support 1. The slide runs in between the brake blocks 18, 19 (Figure 35 5) and is thereby brought to rest without shock. With the opening of the brake by the controlling means 20 the bell-crank lever 9 is so rocked that its discs 13 engage in the keyways 12 of the slide 6 and now return it with a slower movement into the position according to Figure 1, in which the returning shuttle is taken up, whereupon the movement is repeated.

40 45 The friction discs acting on the slide may of course be constructed otherwise than as illustrated, as is known in itself. Instead of the two discs one or more may be employed; and the discs may be constructed with grooved rims, in which case the slide would have to be provided with friction grooves. A construction is also conceivable in which friction discs or friction rollers act on the slide from both sides, the slide thus running between the friction discs.

55 What I claim is:—

1. Apparatus for reciprocating the implements used for weaving in looms, comprising continuously rotating friction discs, a slide adapted to be reciprocated by said discs, and a driving stop on said slide, said driving stop being adapted to communicate

motion from said slide to the said weaving implement.

2. Apparatus for reciprocating the implements used for weaving in looms, comprising two continuously rotating friction discs, a slide adapted to be reciprocated by said discs, and a picker on said slide, said picker being adapted to communicate motion from said slide to said weaving implement. 65

3. Apparatus for reciprocating the implements used for weaving in looms, a slide capable of being reciprocated across the loom, said slide being formed with keyways running in the direction of its motion, friction discs adapted to engage in said keyways, means for causing said friction discs to rotate continuously in such a direction as to drive the slide forwards when brought into contact therewith, other friction discs adapted to engage in said keyways, means for causing said second set of friction discs to rotate continuously in the opposite direction to the first set, means for bringing the two sets of friction discs into driving contact with the slide alternately, and a picker on said slide adapted to communicate motion from said slide to said weaving implement. 70 75 80

4. Apparatus for reciprocating the implements used for weaving in looms, comprising continuously rotating friction discs, a slide adapted to be reciprocated by said discs, a picker on said slide adapted to communicate motion from said slide to said weaving implement, and a brake adapted to bring the slide to rest without shock at the end of its travel. 85 90

5. Apparatus for reciprocating the implements used for weaving in looms, comprising a reciprocable slide formed with keyways running in the direction of its travel, continuously rotating friction discs adapted to be brought into engagement with said keyways to throw said slide forward, other friction discs continuously rotating in the opposite direction and adapted to be brought into engagement with said keyways to return said slide to its initial position, a brake adapted to bring the slide to rest without shock at the end of its forward travel, controlling means for releasing said brake, controlling means for bringing the return friction discs into engagement with the keyways in the slide upon release of said brake, and a picker on said slide adapted to communicate motion from said slide to said weaving implement. 100 105 110 115

In testimony whereof I have signed my name to this specification.

GUSTAV FRIEDRICH GIEHLER.
